UNITED STATES PATENT OFFICE.

CHESTER B. ROSENBURGH, OF ROME, NEW YORK.

DESIGN FOR A HAME.

SPECIFICATION forming part of Design No. 20,235, dated October 21, 1890.

Application filed August 30, 1890. Serial No. 363,563. Term of patent 14 years.

To all whom it may concern:

Be it known that I, CHESTER B. ROSENBURGH, a citizen of the United States, residing at Rome, in the county of Oneida and State of New York, have invented a new and original Design for Hames, of which the following is a specification.

This invention has relation to designs for hames.

10 The leading feature of my design consists in providing the side of the hame which is placed next to the collar with a projecting flange extending nearly its entire length.

In the accompanying drawings, Figure 1 is 15 a perspective view of a hame constructed in accordance with my design. Fig. 2 is a transverse section of the same.

Referring to the drawings, A represents a 20 hame of the customary shape formed by a compound curve and provided with the customary trimmings. On the inner side of the hame a flange *a* is formed integral therewith,

the inclined side of said projecting flange and the flat side on the rear face of the body of the hame forming an obtuse angle. A 25 hame provided with said flange represents a neater appearance when placed in position on the horse and has a symmetrical outline which is pleasing to the eye.

Having described my invention, what I 30 claim is—

The design for hames herein described and shown, the same consisting of a hame provided with a flange projecting from its rear face, the incline of the flange forming an obtuse angle with the flat portion of said rear face of the hame, substantially as described. 35

In testimony that I claim the foregoing as my own I have hereto affixed my signature in presence of two witnesses.

CHESTER B. ROSENBURGH.
